UNITED STATES PATENT OFFICE.

EDWARD JARVIS WINSLOW, OF CHICAGO, ILLINOIS.

BUILDING CONSTRUCTION.

No. 844,295.

Specification of Letters Patent.

Patented Feb. 12, 1907.

Application filed October 20, 1905. Serial No. 283,583.

To all whom it may concern:

Be it known that I, EDWARD JARVIS WINSLOW, a citizen of the United States, residing in Chicago, in the county of Cook and State of Illinois, have invented certain new and useful Building Construction, of which the following is a specification.

This invention relates to improvements in building constructions; but more particularly it concerns a peculiar embodiment in which floors of an impervious nature rest directly upon underlying soil and are also carried by and secured to anchors of a peculiar structure whereby upheaval is prevented.

Heretofore great difficulty has been experienced by builders in laying waterproof floors upon soil of the loose and silty nature, such as obtains in reclaimed land. Not only must the floor be supported by an unyielding foundation, but it must also be restrained against upheaval and fracture under the influence of water-pressure. In many localities the subsoil becomes periodically supersaturated with water either through the rise of tides, excessive rains, or the like, and the land becomes soft and marshy during such periods. Moreover, excavations are frequently below the water-line and consequently produce a very considerable pressure upon impervious floors and walls lining such excavations.

It is one object of my invention to so devise a floor and anchoring means therefor that the whole will constitute a structure which may be readily laid by persons of ordinary skill, and when so put in place will be durable and lasting under the most trying conditions.

Another object of this invention is to formulate a reinforced floor adapted to effectively withstand pressures in any direction without fracture or deterioration in its impervious qualities and to also devise a means of securely anchoring such floor to supports adapted to preserve a constant position in the underlying soil.

Still another object of the invention is to formulate an anchoring means which possesses certain unitary characteristics whereby the parts of the same are enabled to be transported conveniently and subsequently assembled with ease and speed into an anchor of any size and proportions.

Yet another object of the invention is to formulate an anchoring means which may be preliminarily positioned in subsoil and subse-

quently be brought to an adjustable attachment to a permanently-laid floor.

An additional object is to produce an anchor which may be so interlocked with the overlying floor that a permanent and durable attachment between the two will be assured.

Another object of the invention is to devise an anchoring means of such form and construction that the same may be readily laid in sections and by suitable compartments in the same may be filled with material constituting the main body of the overlying floor in such a manner that the inserted material may set in place without regard to the supersaturated condition of the subsoil and completely unaffected thereby.

Another object of this invention is to devise an efficient reinforcement for the floor and an easily-applied connection for securely interlocking the same to the underlying anchor.

Other objects and advantages will be in part obvious and in part pointed out herein-after.

The invention accordingly consists in the features of construction, combinations of parts, and arrangements of elements herein-after more specifically embodied as an exemplification of the underlying principles of the invention.

That this invention may be more fully understood and made readily comprehensible to others skilled in its relating arts I have appended as a part of this specification drawings showing an embodiment of the same, and while the underlying principles of the invention may be otherwise applied by modifications falling within the scope of the claims, the herein-stated form is that which I prefer to employ in practice, and now upon making reference to such drawings by means of characters of reference it will be noted that like numerals denote corresponding parts throughout the figures, of which

Figure 1 is a view taken in sectional perspective, showing the general arrangement and application of the invention to an impervious floor, and furthermore illustrating certain details of construction with respect to the features of adjustable connections. Fig. 2 is a perspective view of one form of anchor which I may resort to in applying my invention. Fig. 3 is a view in perspective, showing a section of a preferred form of hollow anchor such as I may use. Fig. 4 is an end view of Fig. 3. Fig. 5 is a perspective view

showing the application of the invention with respect to the devices of high tensile strength employed in connecting the anchor to the overlying floor and additionally strengthening and rigidifying said parts. Fig. 6 is a cross-sectional view showing another modification of the invention in which the anchor *per se* is of an integral cementitious material.

Referring to the drawings, 1 denotes a section of a preferred form of anchor, which is usually of a U shape and has between the side walls one or more compartments 2, which are employed in containing both the connecting devices, hereinafter referred to, and the plastic material constituting the floor substance. Such anchor is preferably of an elongated shape having a relatively wide base-face 3, which is so scoriated as to produce the barb-like projections 4 and 5, which serve to engage with the subsoil and prevent any displacement of the anchor. In the ordinary manner of using such anchor it is first embedded in the soil to an appropriate height and appropriately spaced apart from its neighbor. The connecting devices 6 are then positioned within the compartments provided for the purpose. Such connections are of a lateral configuration, such as will correspond with the shape of the compartment, which preferably enlarges at its base, so that the connection will be interlocked therein. Preferably such connection is in the form of a flat plate in order that it may with greater facility be inserted into the compartment in a proper interlocking position. To further brace and strengthen the structure, a series of tension members 7 may be passed through suitable orifices in the connection devices 6. After inserting said connection devices in place the reinforcements 8 and 9 are passed through corresponding apertures in the upper end of the same, and it is around these reinforcements that the main body of the floor is to be molded. Such reinforcements may consist of a plurality of relatively small tension members 8 and one or more members 9 of any desirable shape, such as a U or the like. It will be understood that the anchoring of the full length of the floor will be made up by running together any suitable number of sections, which, as shown, are open at their ends. Within the compartments afforded by the sections is inserted a cementitious material 10, and the latter may be thoroughly forced through all crevices and interstices of such compartment, as well as into various apertures in the connecting device, as indicated by 11. As will be understood, this cementing material is thoroughly protected from the surrounding soil and may harden and set at leisure to form a perfect bond between all contacting portions. Since the sections are open at ends, the chamber or compartment of one merges into that of the adjacent, and

as the whole is filled by the cementitious mass therein inserted such sections are firmly bonded together as soon as the cement is hardened.

After applying certain additional transverse strengthening-reinforcements 12 and 13 the main body of the floor 14 is applied, and preferably such main body, which is of cementitious material, merges with that introduced into the compartments of the underlying anchor in such a way as to form between the anchors and the floor a rigid integral structure. It will be obvious that sufficient time may be allowed after setting up the anchors and before laying the floor to allow the former to assume a comparatively permanent position, and after the whole is assembled the complete structure will possess great rigidity between all parts. A finishing-coat of hard wearing material 15 may be applied to the floor, if so desired.

In the modified form of anchor shown in Fig. 2, and to the left of Fig. 1, the transversely-extending floor-supporting girders 16 are employed. These girders may, if so desired, be constructed mainly of plastic material, having embedded therein suitable reinforcements 17. Such girders are usually embedded in the subsoil and are carried at intervals by suitable pyramid anchors 18, 95 having faces depressed that they may be better engaged by the soil. Protruding from the upper end of such anchors is a fixing-plate 19, through which the reinforcements of the floor may be passed. In the form shown in Fig. 1 such extension 19 has a double set of orifices, the lower for the reception of the strengthening members 17 and the upper for the reception of the aforesaid members 8 and 9. In this instance the top of the anchor 105 will be suitably channeled to receive the concrete girder 16.

The form illustrated by Fig. 2 is especially applicable for service in floors in which the same rests directly upon the upper flat surface of the anchor and has reinforcing members passing through the extension 19. The relative arrangement of such extension 19 with the main body of the anchor may be that shown by Fig. 6, in which a slightly-modified contour is given to such anchor.

From the foregoing it will be understood that while I prefer to employ cementitious materials for carrying out my invention, I may obviously resort to other expedients, 120 though I regard the use of cement and other plastic materials as of the most improved construction.

Since many changes could be made in the above constructions and many embodiments 125 of this invention might be made without departing either from the spirit or scope thereof, although from a cursory inspection such changes might seem to apparently widely differ therefrom, I propose that all matter 130

contained in the above description or shown in the accompanying drawings shall be interpreted merely in an illustrative and not in a limiting sense. Furthermore, I desire it to be understood that the language in the following claims is intended to cover all the generic and specific features of this invention and all statements of the scope thereof which as a matter of language might be said to fall therebetween.

I accordingly claim, and desire to secure by Letters Patent of the United States, the following:

1. In a building construction an impervious floor of plastic material, a floor-anchor having a recess and means therein for securing the same to reinforcements embedded in the overlying floor.

2. In a building construction a cement floor resting directly upon underlying soil, a floor-anchor having a chamber and means for securing the same to said overlying floor, said means arranged in said chamber in predetermined positions permanently maintained said anchor being embedded in the soil underlying said floor.

3. In a building construction a floor, a sectional floor-anchor embedded in the soil underlying said floor having a compartment and means therein positionable for securing the anchor to an overlying floor.

4. In a building construction a floor, a sectional floor-anchor embedded in the soil underlying said floor, having a compartment a floor resting upon the upper end of said anchor and means therein for securing the same to an overlying floor, through reinforcements embedded therein.

5. In a building construction a floor, a sectional floor-anchor embedded in the soil underlying said floor, having a compartment and means adjustable therein and adapted for being retained permanently in a predetermined position, said means extending into attachment with an overlying floor.

6. In a building construction a floor, a sectional floor-anchor embedded in the soil underlying said floor having a compartment and means located therein in a predetermined permanently-maintained position for affixing the same to reinforcements in an overlying floor.

7. In a building construction a floor, a sectional floor-anchor embedded in the soil underlying said floor, having a compartment, a device therein for connecting the same to an overlying floor, and means for permanently positioning the aforesaid parts.

8. In a building construction, a sectional floor-anchor provided with a compartment, a device therein extending to reinforcements embedded in an overlying floor, and means within said compartment for permanently positioning said device to said anchor.

9. In a building construction a floor, a

sectional floor-anchor embedded in the soil underlying said floor provided with a compartment, a floor resting upon the upper end of said anchor and means therein comprising a plastic composition for securing the anchor to an overlying floor.

10. In a building construction a floor, a sectional floor-anchor embedded in the soil underlying said floor provided with a compartment and means therein comprising a hardening plastic mass for adjustable and permanently securing the same to reinforcements embedded in an overlying floor.

11. In a building construction a floor, a sectional floor-anchor embedded in the soil underlying said floor having a compartment, a device therein for connecting the same to an overlying floor, and a plastic composition within said compartment and embedding said device for permanently positioning the same.

12. In a building construction, a sectional floor-anchor provided with a compartment, a device therein extending to reinforcements embedded in an overlying floor, and a plastic composition within said compartment and embedding said device whereby the same is permanently positioned.

13. In a building construction, a floor-anchor of substantially a U shape and means embedded between the side walls thereof for permanently attaching it to reinforcements in an overlying floor.

14. In a building construction, a floor, a horizontally-elongated floor-anchor provided with vertically-extending compartments and means permanently affixed therein for attaching it to an overlying floor.

15. In a building construction, a floor-anchor provided with a compartment, a device therein extending into attachment with reinforcements embedded in an overlying floor the material whereof extends into said compartment and securely positions said device in place.

16. In a building construction, a floor-anchor provided with a compartment having an opening in the upper end thereof and an overlying floor composed essentially of plastic material which extends into and fills said compartment.

17. In a building construction, a horizontally-extending floor-anchor comprising a plurality of like sections each having compartments, and an overlying floor the material whereof extends into and fills said compartments.

18. In a building construction, a floor-anchor having a recess and an overlying floor, the material whereof extends into said recess to form an interlocking engagement with said anchor.

19. In a building construction, a floor-anchor comprising a plurality of abutting like sections each provided with compartments,

- devices therein and extending to engagement with suitable reinforcements embedded in an overlying floor, the material whereof extends into said compartment, whereby the whole is interlocked together. 5
20. In a building construction, a floor-anchor of elongated-U shape having a compartment flaring into an enlarged bottom, and a similarly-shaped retaining device therein and 10 extending into engagement with reinforcements embedded in an overlying floor.
21. In a building construction, a floor-anchor having a compartment whereof portions flare into an enlargement, and a like-shaped 15 retaining device interlocking in said compartment and extending into engagement with an overlying floor.
22. In a building construction, a floor-anchor provided with a horizontally-extending 20 elongated compartment opening in the top, retaining-plates of like contour spaced at intervals in said compartment and affixed at their upper ends to reinforcements embedded in an overlying floor, and at their lower ends 25 similarly united to reinforcements extending through said anchor.
23. In a building construction, a floor-anchor having a compartment provided with lateral extensions, a like-shaped retaining device 30 interlocking in said compartment and extending into engagement with an overlying floor, and a plastic composition within said compartment and embedding and permanently securing in place said device. 35
24. In a building construction, a floor-anchor, having a substantially inverted - T-shaped compartment, a like-shaped retaining device therein extending into engagement with reinforcements in an overlying floor, the 40 material whereof extends into said compartment and securely positions said retaining device. 45
25. In a building construction, a floor-anchor comprising a plurality of similar abutting sections each having one or more compartments, devices therein in interlocking engagement with the walls of said compartments and extending into attachment with reinforcements embedded in an overlying floor, the material whereof extends into said compartments and thereby securely interlocking the whole together. 50
26. In a building construction, a sectional floor-anchor having a compartment open at the top and closed at the bottom, a device 55 therein for connecting the same to an overlying floor and means for permanently interlocking said device to the anchor.
27. In a building construction, a sectional floor-anchor provided with a compartment, a 60 device therein and in an interlocking engagement therewith, and an interfitting means for permanently securing the same in place, said device extending into connection with an overlying floor. 65
28. In a building construction, a sectional floor-anchor provided with a compartment, a device therein adjustably extending to reinforcements embedded in an overlying floor and a plastic composition within said compartment and embedding said device in an interlocking manner whereby the same is permanently positioned. 70
29. In a building construction, a floor-anchor provided with a compartment, a perforate plate therein corresponding in lateral outline thereto, reinforcements embedded in an overlying floor extending through perforations in said plate, like members embedded in the anchor and extending through the 75 lower end of said plate, and a plastic composition within said compartment and filling the interstices of the same and the perforations in said plate whereby the whole is securely interlocked together. 80

EDWARD JARVIS WINSLOW.
